FILLING MACHINE

Joseph L. Lawrence, San Francisco, Calif., assignor to Walter King, San Francisco, Calif.

Application April 3, 1937, Serial No. 134,857

3 Claims. (Cl. 226—99)

This invention relates to filling machines of the type which will measure a predetermined quantity of material and discharge the same into a receptacle. More specifically it is of the suction 5 filler type in which means are provided for drawing a quantity of material into a measuring cylinder or chamber and to thereafter discharge the same into a container.

It is an object of this invention to provide a 10 device of the class described which will completely discharge all material drawn into the measuring area and thereby prove self-cleaning.

It is another object of the invention to provide a device of this character which will not only be 15 self-cleaning but which will cut the flow of the material being handled off sharply at the point of discharge, thus eliminating dripping between positioning of empty receptacles.

Additional objects of the invention are the 20 provision of a filling machine which is compact, inexpensive to construct and operate, as well as one which has a desirable minimum of working parts.

In general, these and other objects to become 25 apparent as this specification proceeds, are attained by the provision of a filler in which a piston is caused to reciprocate in an oscillating cylinder. The oscillating cylinder is provided with charge and discharge ports adapted to be 30 alternately brought into registry with corresponding ports in the casing surrounding the cylinder.

Another novel feature of the invention is the provision of a "no-can no-fill" control wherein a 35 clutch, governing movement of the piston and oscillation of the cylinder, is adapted to be controlled by oncoming empty receptacles. In the absence of proper introduction of empty receptacles the clutch control is not effected and consequently no material is handled by the device. In addition, I provide novel means for adjustment of the stroke of the piston in the cylinder to determine the measurement of the substance 40 being handled.

I am conversant with many of the fillers of this 45 class and particularly those which employ the vacuum-suction method of measuring followed by discharge to a container. It is observed that substantially all, if not all, of the prior art structures leave much to be desired. One of the most serious objections seems to be the fact that they are not wholly self-cleaning, e. g., they do not discharge the material down to the last drop and are therefore inaccurate and they do not provide 50 for the all important factor of cleanliness. An

example of this is found in these devices which utilize a valve of considerable area through which the material must pass into the measuring chamber. In those devices varying quantities of the material are left within the valve means at the 5 conclusion of each individual operation which tends to materially decrease the efficiency of the measuring means.

It is believed that these and other objections to the prior art structures are overcome in the 10 present invention.

In the drawings forming a part of this specification,

Figure 1 is a longitudinal section of the filling and measuring means forming a part of the sub- 15 ject matter of this invention.

Figure 2 is a top plan view of the whole device with the cover means removed to show the clutch and other control means,

Figure 3 is a side elevation of the subject matter- 20 of Figure 2,

Figure 4 is a sectional view along the line 4—4 of Figure 2,

Figure 5 is a sectional view along the line 5—5 of Figure 1 showing the relation of charge and 25 discharge ports in the oscillating cylinder and the casing therefor during the discharge of material,

Figure 6 is a sectional view of the subject matter of Figure 5 during the charging of the cylinder with material, 30

Figure 7 is a sectional view along the line 7—7 of Figure 2, showing the detail of the clutch,

Figure 8 is a top plan view of the subject matter of Figure 7 with certain parts broken away 35 for sake of clarity,

Figure 9 is an enlarged detail of the eccentric mounting for the connecting rod of the piston, and

Figure 10 is a fragmentary sectional view, taken 40 along the line 10—10 of Figure 1, illustrating the eccentric mounting of Figure 9 with the connecting rod secured thereto.

The numeral 15 indicates a cylindrical housing 45 for an inner cylinder 16 which is adapted to be oscillated in a manner presently to be described. The outer cylinder 15 is bolted or otherwise secured to the housing 17 provided for a clutch mechanism and these elements, together with 50 conventional speed reducer 18 and a prime mover 19, are supported on a table 20 by the stand- ard 21.

Cylinder 15 has a head 22 bolted thereto, as at 55 23, and the latter projects inwardly to provide a

bearing 24 for the oscillated cylinder 16 (see Figure 1).

Charges of the material to be handled are received by the cylinder 16 through a top port 25 therein and, in turn, from a source of supply through the pipe 26 secured in the extension 21 at the top of the cylinder 15, which has a port 28 brought into registry with the port 25 during oscillation of the cylinder 16 (see Figure 6).

10 The measured quantities of the material being handled are discharged through the ports 32 and 33 in the cylinders 16 and 15, respectively, (see Figure 5) as the oscillations of cylinder 16 bring the two into registry. It will be noted from Figure 1 that ports 32 and 33 take the form of elongated slots. It has been found that by the provision of ports of this character the accurate and complete discharge of materials is greatly facilitated.

20 The measurement of materials within cylinder 16 is caused upon operation of the piston 35 therein. This piston has a connecting rod 36 which is adjustably connected to the eccentric drive, illustrated to best advantage in Figures 1, 9 and 10, by 25 means of an enlarged elongated loop 37.

A frame 40 secured at right angles to the end of shaft 41 in any conventional manner, is provided with a T-shaped slot 42 to receive a block 43.

30 A bolt 44, secured thereto, projects outwardly through the slot 45 in the plane of the shaft 41. Since bolt 44 serves as a stub shaft for connecting rod 36, and adjustable eccentric drive thereof is desirable, the following means is provided for adjustment of the block 43 in slot 42. Bolt 46 35 has a shoulder 46a received by a bore (shown in dotted lines in Figure 9) in the bottom of frame 40. The shoulder 46a has an annular groove 47 which is engaged by a pin 48 through frame 40. Thus bolt 42 is retained against longitudinal 40 movement but left free for turning. Since bolt 42 has a threaded connection with block 43, it will be seen that by turning its conventional head, block 43 will be moved in frame 40 with respect to the axis of shaft 41 to readjust the eccentric 45 drive.

A sleeve bearing 55 on bolt 46 has a shoulder 56 set flush with the face of the frame 40, and is adapted to be retained by a nut 57, and a common washer, on bolt 44.

50 The connection of the connecting rod to the mechanism just described is effected through the provision of a sleeve bearing 58 on sleeve bearing 55. A rim or shoulder 59 on bearing 58 engages one side of the loop 37 of the rod 36 and the opposite side is engaged by a common washer and a ring nut 60.

It will thus be seen that the loop 37 and its bearing member 58 are free to be driven by rotation of shaft 41 and the eccentrically mounted stub shaft or bolt 44 to reciprocate the piston 35.

60 The clutch about to be described is of the one-cycle type. That is one complete cycle thereof effects the charging of cylinder 16 and the discharge of material therefrom. As heretofore pointed out, it is desirable in devices of this class that some provision be made to prevent discharge of the material being handled in the absence of a can to receive the charge. It was with this factor 65 in mind that the novel clutch control means forming a part of the subject matter of this invention was devised.

It will be noted that shaft 41 is journaled in suitable bearings 65 and 66 in post 67 (see Figure 75 3) and the housing head 68, respectively.

A gear 70 and a clutch plate 71 integral therewith, are free on shaft 41. Gear 70 engages a gear 72 mounted on shaft 73, which in turn, is rotated by its connection to the reducing gear 18 and the prime mover 19. Thus, while the running 5 of the prime mover 19 (here shown to be an electric motor) is constant, it will be understood that gear 70 and the integral clutch plate 71 are merely idling on shaft 41 subject to engagement of the clutch.

10 A second clutch plate 74 is pinned to the shaft 41, as at 75, and engagement of the two clutch plates is effected in the following manner: Clutch plate 71 has a pin 76 wedged therein with a beveled end 77 projecting in the path of the pin 15 78, in the bore 89 in clutch plate 74, and having a similar beveled end 79. The pin 78 is provided with a spring 80, in its bore 81, with which it is adapted to telescope. The function of spring 80 is to urge the pin outwardly into engagement 20 with pin 76 in clutch plate 71. This movement is limited by means of a pin 82 in a slot 83 in the said pin (see Figures 7 and 8).

The clutch thus comprised is effectively controlled by means of a finger 85, on shaft 86, 25 which rides in a slot 87 in clutch plate 74 to engage pin 78. As will be noted from Figure 8, pin 78 is provided with an angular slot 88 between its beveled face 79 and the slot 83. The slot 88 consists in a cut made at a 45° angle terminating in a transverse cut in the pin 78. Thus when finger 85 is riding in the slot 87 and comes into engagement with the angular slot or groove 88, pin 78 is moved against the tension of the spring 80 into the clutch plate 74 and out of engagement 30 with the complementary pin 76 in clutch plate 71.

The movement of finger 85 and hence control of the clutch mechanism is governed by the introduction of cans into the filling area and this 40 constitutes the "no-can no-fill" feature of the apparatus. A star wheel 90 is disposed beneath the housing 17 with its arms projecting into the filling area for engagement by cans 91 on conveyor 92. The star wheel 90 is pinned to a shaft 45 projecting through the dependent member 93 on housing 17, and to the other end of which shaft a collar member 94 is secured inside of the housing 17 (see Figures 1 and 3). The collar 94 in the present adaptation of the invention, has three 50 grooves 95 in its upper face, corresponding to the number of arms on the star wheel 90, for engagement with a pin 97 in the link 98 which is secured to shaft 86.

The said shaft 86 is journaled in the post 67 55 and a second post 99, and the said link 98 is secured to that end of the shaft which projects beyond post 67.

As pin 97 is normally in one of the grooves 95 in the top of collar 94, finger 85 fixed on 60 shaft 86 is held in engagement with pin 78 and the clutch is thus retained in disengaged position. When a can, 91, moving along on conveyor 92, contacts one of the arms of the star wheel 90, collar 94 is turned against pin 97 and 65 the latter is forced out of the groove 95 and up on the flat top surface of the collar 94. Through lever 98 shaft 86 is partially turned and finger 85 is moved out of engagement with pin 78. Spring 80 thereupon urges pin 78 into engagement 70 with the complementary pin 76 and the clutch is engaged for its one cycle. The pin 97 moves over the flat top surface of collar 94 to the next groove 95 and when it drops into the same, finger 85 is caused to move back into slot 87 for 75

engagement with pin 78 as clutch face 74 revolves. When the rotation of clutch plate 74 is complete, finger 85 enters the slot 88 in pin 78 and draws the same out of engagement with the pin 76 to 5 disengage the clutch.

Oscillation of the cylinder 16 is accomplished through the medium of the linkage shown to best advantage in Figures 2 and 4. Here it will be noted that the cylinder 16 has a collar or flange 105, at its inner end, which is provided with a projection 106 for engagement with a link 107. The link 107 is pivotally connected with a link 108 fastened on one end of the stub shaft 109 suitably journaled in the bottom of housing 17 as at 110. At the opposite end of the shaft 109 I provide upstanding arm 111 having a roller 112 disposed at right angles thereto to ride in the cam slot 113 in clutch plate 74. Due to the shape of the cam slot 113 (see Figures 2, 7 and 8) it will be appreciated that when the clutch is engaged 20 and plate 74 revolves with shaft 41, arm 111 is moved to the left (looking at Figure 4) and, through the linkage just described, cylinder 16 is partially turned in a counter-clockwise direction 25 (looking at Figure 5) to bring port 25 into registry with port 28 in cylinder 15 (see Figure 6). The movement of roller 112 in slot 113 is such that these ports remain in registry sufficiently long 30 enough to permit a full charge of the material being handled to be drawn into cylinder 16. As the cycle of the clutch is completed, cylinder 16 is turned back to its original position (see Figure 5) to close port 28 and to bring ports 32 and 33 into registry for the discharge stroke of piston 35, in which position it remains between 35 cycles of the clutch.

It will be appreciated from the foregoing description and Figure 1 of the drawings that in order to adjust the mechanism to handle different quantities of material, only readjustment of the connections between connecting rod 36 and shaft 41 is necessary. In other words, the length of the charge stroke of piston 35 in cylinder 16 is the determining factor.

45 As previously stated, by turning the head of bolt 45, block 43 in frame 40 is caused to move with respect to shaft 41, and thus the off-center adjustment of the stub-shaft 44 is effected. In this manner the length of the stroke of piston 35 in cylinder 16 is determined. It is to be understood that in making the adjustment it is necessary to first loosen nut 57 on stub shaft 44, to the end that block 43 will be free to move in frame 40 upon the turning of the head of bolt 45. By 50 the same token when the desired eccentric position of stub shaft 44 has been determined, nut 57 is tightened to lock the block 43 in position.

In order to carry out the self-cleaning principle of the invention, it is also necessary to adjust 55 for a full stroke of piston 35 against the cylinder head 22. By loosening nut 60, binding loop 37 of connecting rod 36 to the bearing member 58, piston 35 is free to be adjusted against cylinder head 22. In this adjustment only sufficient clearance is provided to prevent the piston 35 striking the head 22.

The operation of the apparatus thus described is as follows: When the preliminary adjustments have been made to determine the length of the 60 stroke of the piston 35, e. g., the measurement of the material to be handled, pipe 26 is placed in communication with a source of supply of the material to be handled and conveyor 92, for cans 91, is started. As the cans 91 progress and individually engage the arms of the star wheel 90

the latter is turned to raise pin 97 out of engagement with grooves 95 on the top of collar 94. Pin 97 moves over the flat surface of the top of collar 94 toward the next succeeding groove 95. Finger 85, through link 98 and shaft 86, is thus caused to move out of engagement with pin 78, allowing spring 80 to urge the same into engagement with the complementary pin 76. The clutch is thus engaged for its one cycle movement.

As shaft 41 is caused to rotate upon engagement 10 of the clutch piston 35 is withdrawn from the head of cylinder 16 while simultaneously the cam action of slot 113 on roller 112 has, through the described linkage, caused cylinder 16 to oscillate about piston 35 to bring the intake port 25 into 15 registry with port 28 in cylinder 15. As piston 35 continues its movement a charge of the material is sucked into cylinder 16. At the moment piston 35 has been withdrawn its full stroke away from the head 22 of cylinder 16 the cam slot 113 will cause further oscillation of cylinder 16 to close port 25 and swing ports 32 and 33 into registry for the discharge stroke of piston 35. Said piston 35 is thereupon driven the full length of cylinder 16, forcing the material within the cylinder through the ports 32 and 33 into the positioned can 91.

At the precise moment piston 35 reaches the head 22 of cylinder 16, pin 97 has dropped into the next succeeding groove 95 in collar 94 and 30 finger 85 has once again engaged pin 78 to urge the same out of engagement with pin 76, and against the urge of spring 80, thus disengaging the clutch.

It will thus be understood that in the absence 35 of a can there will be no handling of the particular material and that the same will remain in its source of supply and the conduit therefrom, entirely outside of the mechanism forming the subject matter of this invention. In this way possible contamination of the substance being handled is greatly minimized and unnecessary wear on the apparatus is obviated.

As hereinbefore stated, one of the particular advantages of the present invention lies in the 45 fact that the measuring cylinder 16 is completely self-cleaning and that no material remains therein from one filling to the next. This is a highly desirable factor when consideration is given to the fact that machines of this character frequently handle edible substances and other materials which have a highly corrosive effect on equipment of this sort.

It is to be appreciated and understood that in the drawings forming a part of this application 55 I have illustrated and described but one form of the invention and while that is the preferred form, the principles of the invention are applicable to many other variations and modifications without departing from the spirit thereof.

Having thus described my invention, what I claim and desire to secure by grant of Letters Patent is:

1. In a filling device, the combination of a 65 housing for a cylinder, a cylinder therein, said housing and said cylinder having intake and discharge ports adapted to be alternately brought into registry upon oscillation of said cylinder, a piston in said cylinder, means for reciprocating the piston to successively charge and discharge 70 material from the cylinder, a clutch for said reciprocating means including two elements engageable by yieldable means, control means for said clutch comprising a receptacle actuated member on a shaft, a collar having a plurality of 75

- grooves on the opposite end of said shaft, a second shaft at right angles to the first, a link fixed at the end of the second shaft adjacent said collar, a pin on said link normally disposed in one of said grooves in said collar, a finger fixed on the second named shaft at the end opposite to the link and acting upon said yieldable means in said clutch to normally disengage the same when said pin is in one of said grooves on said collar but retractable upon movement of said receptacle actuated member and the raising of said pin to the normal plane of said collar.
2. In a filling device of the type in which a piston is reciprocated within a cylinder to successively draw and discharge a quantity of material, means for reciprocating the piston comprising the combination of a shaft, a slotted frame mounted on the end thereof, a block in said frame having a stub shaft projecting through the slot in a plane parallel to the axis of said shaft, a sleeve fixed on said stub shaft, a piston
- 5
- 10
- 15
- 20

rod having an elongated slot in the end thereof, a bearing member for the sleeve on the stub shaft fixed in the slot in said piston rod.

3. In a filling device of the type in which a piston is reciprocated within a cylinder to successively draw and discharge a quantity of material, adjustable means for reciprocating the piston comprising the combination of a shaft, a slotted frame mounted on the end thereof, a block in said frame having a stub shaft projecting through the slot in a plane parallel to the axis of said first named shaft, means for determining the position of said block in said frame with respect to the first named shaft, a sleeve fixed on said stub shaft, a piston rod having an elongated slot in the end thereof, said piston rod being operatively connected to said shaft by a bearing member in said slot and disposed on said sleeve, and retainer means fixing the position of said bearing member in said slot.

JOSEPH L. LAWRENCE. 20
